UNITED STATES PATENT OFFICE.

JAMES C. MOCK, OF DETROIT, MICHIGAN.

INSULATED RAIL-JOINT.

SPECIFICATION forming part of Letters Patent No. 761,526, dated May 31, 1904.

Application filed October 26, 1903. Serial No. 178,495. (No model.)

To all whom it may concern:

Be it known that I, JAMES C. MOCK, a citizen of the United States, residing at Detroit, in the county of Wayne, State of Michigan, have invented certain new and useful Improvements in Insulated Rail-Joints; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an insulated joint for railway-rails especially designed for use in connection with the block-signal system; and it consists in the construction and arrangement of parts hereinafter fully set forth, and pointed out particularly in the claims.

The object of the invention is to provide an insulated rail-joint of the character described with an auxiliary-rail section or analogous supporting-bar adapted to receive and carry the weight of the passing train at said joint, so as to obviate the vertical movement of the ends of the service-rails as incident to the ordinary insulated joint, thereby rendering the joint firm and smooth to the passing train and obviating undue wear and injury to the service-rails.

The above object is attained by the structure illustrated in the accompanying drawings, in which—

Figure 1 is a perspective view of an insulated rail-joint involving my invention. Fig. 2 is a side elevation of said joint. Fig. 3 is a plan view thereof. Fig. 4 is a transverse section as on line 4 4 of Fig. 2.

Referring to the characters of reference, 1 designates the service-rails, the meeting ends of which are insulated by inserting between them suitable insulated material 2. Supporting the ends of the service-rails and extending thereunder is a chair or bridge-plate 3, having along one edge a vertical flange 4. Interposed between the base of the service-rails and said bridge-plate is a channeled piece of insulating material 5, whose marginal flanges 6 and 7 embrace the edges of the base

portion of said rails, whereby the meeting ends of the service-rails are insulated from the bridge-plate 3. Lying adjacent the ends of the service-rails and crossing the insulated joint between them is an auxiliary rail 8, the top of which is sufficiently high to receive the tread of the wheels of a train or car when passing the joint between the service-rails, whereby the load is borne by said auxiliary rail and the insulated joint between the service-rail sections is relieved from the weight and wear incident to the passage of the train or car thereover.

Owing to the fact that the meeting ends of the service-rails are supported by the insulating material 5 under ordinary conditions the weight of the train upon said rails would batter down said insulation and allow considerable play to the rails at the joint. The presence of the auxiliary rail 8, however, relieves the joint from the load, which is carried by said auxiliary rail, thereby obviating a loose and imperfect joint between the rail-sections, as would otherwise result.

The auxiliary rail 8 may be a section of an ordinary rail cut the proper length and having one side of its base removed to allow it to be placed upon the bridge-plate 4 so that the top thereof will stand adjacent the top of the service-rail sections, the base 9 of said auxiliary rail engaging the vertical flange 4 of the bridge-plate. To bring the top of the auxiliary rail to the proper height to receive the tread of the wheel when passing the joint, a steel filler 11 is placed between the base of the auxiliary rail and said plate. Where the auxiliary-rail section is rolled expressly for the purpose of forming this joint, the employment of the steel filler will not be necessary. To secure the auxiliary rail to the bridge-plate, a series of bolts or rivets 12 are passed through the base of said rail and through said plate, as shown.

The ends of the service-rails are connected by a fish-plate 13, which is secured in place by the bolts 14, which pass through the web of the auxiliary rail, the wood filler 15, interposed between said rails, the web of the service-rails, and the fish-plate.

The flange 7 of the channeled piece of insulation extends upwardly between the base 16 of the service-rail and the base of the auxiliary rail, while the tops of said rails are insulated from each other by the inserted strip of insulation 17. The fish-plate is insulated from the web and base of the service-rails by the interposed strip of insulation 18.

To prevent the establishment of electric communication between the service-rails and the auxiliary rail through the bolts 14, said bolts are surrounded where they pass through the web of the auxiliary rail and through the fish-plate by an insulating-bushing 19, while the metal washers 20 carried by said bolts are backed by the washers 21 of insulating material. It will now be evident that the ends of the service-rails are insulated from each other and from the bridge-plate which supports them, and it will also be evident that the auxiliary rail is insulated from the service-rails, while said auxiliary rail is so positioned as to receive the load at the rail-joint when the train or car is passing. The top of the auxiliary rail is beveled off at each end, as shown at 22, leaving the higher portion upon the inside of the rail, which extends entirely across the rail at the longitudinal center thereof. This formation permits the load to be transferred gradually from the service-rail to the auxiliary rail and gradually transferred from the auxiliary rail to the service-rail as the wheels of the cars are passing the joint.

The filling of wood or analogous material 35 15 between the auxiliary rail and the main rails serves to brace the auxiliary rail and prevent it from tipping inwardly toward the main rails when the load is transferred thereto.

I have illustrated this invention in connection with an auxiliary-rail section formed from a piece of T-rail. It is evident that where the auxiliary rail is rolled expressly for this purpose its base will rest directly upon the bridge-plate, while the top thereof will stand flush 45 with the top of the service-rails.

Having thus fully set forth my invention, what I claim as new, and desire to secure by Letters Patent, is—

1. In an insulated joint, the combination of 50 the service-rails insulated from each other, the auxiliary rail fastened to the adjoining ends of the service-rails and insulated therefrom, the top of said auxiliary rail being sufficiently

high to receive the tread of the car-wheels passing over the joint.

55

2. In an insulated rail-joint, the combination of the service-rails having their adjoining ends insulated from each other, the auxiliary rail crossing the joint between the service-rails and being of sufficient height to receive the tread of the wheels passing the joint, insulating substance between the auxiliary rail and at least one of the service-rails to separate said rails electrically.

60

3. In an insulated rail-joint, the combination 65 of the insulated service-rails, an auxiliary rail crossing the insulated joint between the service-rails, and a filler of insulating material interposed to separate the running-rails from said auxiliary rail.

70

4. In an insulated rail-joint, the combination 75 of the service-rails insulated from each other, the auxiliary rail crossing the insulated joint between the service-rails and lying adjacent thereto, said auxiliary rail being insulated from the service-rails, and a bridge-plate supporting the ends of the service-rails and said auxiliary rail.

75

5. In an insulated rail-joint, the combination 80 of the service-rails insulated from each other, the auxiliary rail crossing the joint of the service-rails and being of sufficient height to receive the tread of the wheels.

80

6. In an insulated rail-joint, the combination 85 of the running-rails insulated from each other, the auxiliary rail fastened to the adjoining ends of the running-rails and insulated from said rails by an inserted strip of insulation.

85

7. In an insulated rail-joint, the combination 90 of the main rails having their adjoining ends insulated from each other, the auxiliary rail crossing the joint between the main rails and fastened to the adjoining ends thereof, the top of said auxiliary rail being sufficiently high to receive the tread of the car-wheels, insulation 95 inserted between the main rails and said auxiliary rail, a bridge-plate supporting the main rails and said auxiliary rail and a strip of insulation between the main rails and said plate.

90

In testimony whereof I sign this specification in the presence of two witnesses.

100

JAMES C. MOCK.
